UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

IGNITION SYSTEM.

Application filed February 20, 1922. Serial No. 537,985.

To all whom it may concern:

Be it known that I, WILLIAM W. HAWKINS, a citizen of the United States, and resident of Brooklyn, in the county of Kings and State of New York, have invented certain new and useful Improvements in Ignition Systems, of which the following is a full, clear, concise, and exact description, reference being had to the accompanying drawings, forming a part of this specification.

My invention relates to an ignition system wherein each spark plug of an engine is connected with the secondary of one of a plurality of ignition coils which are successively excited from a source of current common to all of the ignition coils. It contemplates the provision of a generally improved system of this class.

As the characteristics, principal objects, and advantages of my improved ignition system will best be understood from a description read in connection with illustrative drawings, I shall proceed at once to a description of the accompanying drawings in which

Figure 1 is a diagrammatic representation of an ignition circuit embodying my invention;

Figure 2 illustrates how the primary, secondary and tertiary windings of one of the ignition coils may be mounted upon a straight core, and

Figures 3 to 6 inclusive illustrate different arrangements of said primary, secondary and tertiary, windings upon a rectangular core.

Similar characters of reference refer to similar parts throughout the several views.

Referring first to Figure 1, reference character 10 indicates a four cylinder engine provided with spark plugs 11-11, each of which is adapted to be supplied with high tension ignition current, at the proper time in the cycle of the engine operation, from one of a plurality of ignition coils, each of the ignition coils being indicated as a whole by reference numeral 12. Each ignition coil comprises three windings, namely, a

primary winding P, a secondary winding S, and a tertiary winding T. The tertiary winding may be in all respects similar to the primary. The secondary comprises a relatively greater number of turns of comparatively fine wire, while the primary and

tertiary windings comprise a lesser number of turns of relatively larger wire. The three windings of each ignition coil are mounted upon a suitable magnetic core C (not shown in Figure 1).

One end of each of the secondary windings is grounded in the usual manner, the other terminals of said secondaries being connected with the insulated terminals of spark plugs 11-11. One end of each of the primaries P is connected with one of the segments 13-13 of a timer mechanism 14. The other ends of the primaries are brought together as illustrated, and are electrically connected with each of two contacts 15 and 16. Each of the contacts 15 and 16 is adapted to be engaged by a movable switch 17 which in turn is electrically connected with one of the terminals of an alternating current magneto 18. The other terminal of the magneto is grounded. Switch 17 is moved into contact with the button 16 when the engine is to be started, and is shifted to contact with button 15 when the engine is running. One end of each of the tertiary windings is grounded, the other ends of said tertiary windings being brought together, and being electrically connected to the stationary or insulated contact of an interrupter mechanism 19. The movable interrupter contact is grounded; hence the tertiary windings are short circuited through ground when the interrupter contacts are closed, the circuits of the tertiary windings being opened when the interrupter contacts separate.

The timer mechanism 14 comprises an engine driven roller 20 which is adapted successively to ground the timer segments 13. The timer roller and the interrupter cam are driven by and in timed relation to the crank shaft of the engine, the timer roller being in complete contact with one of the segments 13 whenever a cylinder is to be fired, the interrupter cam functioning to separate the interrupter contacts, and thereby opening the circuits of the tertiary windings at the instant that the cylinder is to be fired.

At 21, I have diagrammatically illustrated a suitable master vibrator having a condenser connected across its contacts. One end of the vibratory winding is connected with contact button 16, the other end of said winding being connected with the stationary

vibratory contact. The vibratory contact is connected with the ungrounded end of each of the ignition coil primaries P.

Now let us assume that switch 17 is in engagement with contact button 15 (the master vibrator not functioning when the switch is in this position), that the engine is running and that the timer roller has reached the position illustrated in Figure 1. Cylinder 4 is now ready to fire, and a spark will pass at its associated spark plug as soon as the interrupter contacts separate. With the timer roller and interrupter contacts in the position illustrated in Figure 1, the primary of the ignition coil assigned to the spark plug in cylinder 4 is in the closed circuit with magneto 18, but no high tension ignition current is created in the secondary of such ignition coil because the circuit of the tertiary winding of such coil is closed, the tertiary winding serving to neutralize, or substantially to neutralize, any inductive effect which the excitation of the primary would otherwise have upon the secondary. The interrupter cam now separates and opens the circuits of the tertiary windings. The tertiary winding of the ignition coil assigned to cylinder 4, no longer neutralizes the inductive effect of its associated primary upon the secondary winding which is in inductive relation thereto. As a result, a high tension ignition current is induced in said secondary, and a spark passes at the plug of cylinder 4.

The operation just described is repeated as the engine operates, the timer roller 15 successively connecting the primaries of the several ignition coils with the current source through ground, and the interrupter functioning to open the circuits of the tertiary windings each time a spark is to be created in one of the engine cylinders.

When starting the engine, the switch 17 is preferably moved into contact with button 16. With the switch in this position, and with the timer roller in contact with any one of its associated segments 13-13, the master vibrator functions rapidly to interrupt and re-establish the circuit of the ignition coil primary which is connected to ground by roller 20. Otherwise the operation of the system with switch 17 in contact with button 16 is the same as the operation of the system when switch 17 contacts with button 15.

In Figures 2 to 6, I have illustrated various ways of mounting the ignition coil windings upon their associated core C. In Figure 2, I have illustrated an ignition coil comprising a straight core, the primary, secondary and tertiary windings being concentrically disposed around said core as illustrated.

In the arrangement of Figures 3 to 6, I employ a rectangular core which affords a

closed path for magnetic flux created by the excitation of the primary. In the arrangement of Figure 3, each of the windings is mounted upon a separate side or leg of the core C. In the arrangement of Figure 4, 70 the primary and secondary windings are located upon opposite sides or legs of the core, the tertiary winding being formed in two properly connected sections which are mounted upon the other sides or legs of 75 the core.

In the arrangement of Figure 5, the primary and secondary are concentrically arranged upon the same side or leg of the core, the tertiary winding being placed upon 80 the opposite side of the core. In the arrangement of Figure 6, the primary and tertiary windings are disposed upon the same side of the core, the primary being located upon the opposite side. Other suitable coil arrangements will doubtless suggest themselves to persons skilled in the art to which my invention relates.

Having thus illustrated and described my invention, what I claim is new and desire 90 to secure by Letters Patent of the United States is:

1. In an ignition system, a plurality of ignition coils each comprising a primary winding, a secondary winding in inductive 95 relation to the primary winding, a tertiary winding from which the current traversing the primary winding is at all times excluded, said tertiary winding adapted when included in a closed circuit to neutralize the inductive effect of the primary upon the secondary, and distributor mechanism for selectively energizing said primary windings.

2. In an ignition system, an ignition coil comprising a primary winding, a secondary winding in inductive relation to the primary winding, a tertiary winding from which the current traversing the primary is at all times excluded, said tertiary winding adapted when included in a closed circuit to neutralize the inductive effect of the primary upon the secondary, and means for including the tertiary winding in a closed circuit, including the primary winding in 110 circuit with a current source, and then opening the circuit of the tertiary winding, 115 seriatim.

3. In a system of the class described, an ignition coil comprising a core of magnetic 120 material, primary, secondary, and tertiary windings carried by said core, means for periodically including the tertiary winding in a short circuit from which the current traversing the primary is excluded, and 125 means for periodically exciting the primary winding after the tertiary winding has been included in said short circuit.

4. In a system of the class described, an ignition coil comprising in combination a 130

core of magnetic material, primary, secondary and tertiary windings carried by said core, means for periodically connecting the primary winding in circuit with a current source, and for opening said circuit, means adapted prior to the completion of the primary circuit to include the tertiary winding in a short circuit from which the current traversing the primary is excluded, 5 and means for interrupting the circuit of the tertiary winding prior to the interruption of the primary circuit.

5. An ignition system comprising a magnetic core carrying a secondary winding, 15 primary and tertiary windings carried by said core, said last mentioned windings being substantially similar, means for including the primary winding in circuit with a current source, and means adapted when 20 operated to make and break a separate circuit including the tertiary winding, said last mentioned means adapted to complete the circuit of the tertiary winding prior to the completion of the primary circuit, and 25 to open the circuit of the tertiary winding while the primary winding is in circuit with the current source.

6. An ignition coil comprising a magnetic core and primary, secondary and tertiary 30 windings, automatic means for periodically connecting the primary winding in circuit with a current source, and means adapted periodically to include the tertiary winding in a short circuit from which the current 35 from said source is excluded and then interrupt such short circuit while said primary winding is in circuit with said current source.

7. An ignition system comprising an ignition 40 coil which includes a magnetic core carrying primary, secondary and tertiary windings, a high-tension circuit including the secondary winding, a primary circuit including the primary winding and a current 45 source, means for closing and interrupting said primary circuit, and means adapted to include the tertiary winding in a short circuit from which the current from said 50 source is excluded and for interrupting such short circuit, said last named means including said tertiary winding in said short circuit before said primary circuit is closed.

8. An ignition system comprising an ignition 55 coil which includes a magnetic core carrying primary, secondary and tertiary windings, a high-tension circuit including the secondary winding, a primary circuit including the primary winding and a current source, means for closing and interrupting 60 said primary circuit, and means adapted prior to the completion of the primary circuit to include the tertiary winding in a short circuit from which the current 65 from said source is excluded, said last-mentioned means adapted to interrupt such

short circuit prior to the interruption of the primary circuit.

9. An ignition system comprising a plurality of ignition coils, each including primary, secondary and tertiary windings, a 70 current source, means adapted successively to connect said primary windings in circuit with a current source, and means for periodically including the tertiary windings 75 in a short circuit from which the current from said source is excluded.

10. An ignition system comprising a plurality of ignition coils, each including primary, secondary and tertiary windings, a 80 current source, means adapted successively to connect said primary windings in circuit with a current source, and means for short circuiting each tertiary winding prior to the connection of its associated primary in circuit with the current source and for opening 85 the circuit including the tertiary winding while its associated primary is in circuit with the current source, said tertiary windings being at no time in circuit with said source.

90 11. An ignition system comprising a plurality of ignition coils, each including primary, secondary and tertiary windings, a current source, means adapted successively to connect said primary windings in circuit with a current source, and an interrupter mechanism common to all of said tertiary windings, said interrupter mechanism adapted to short circuit all of said tertiary windings prior to the connection of any primary with the current source, and to interrupt the short circuit of the tertiary windings while each primary is connected with the current source, none of said tertiary windings being at any time in circuit 100 with said current source.

105 12. An ignition system comprising a plurality of spark plugs, a plurality of ignition coils each comprising a core and primary, secondary and tertiary windings in 110 inductive relation thereto, each of said secondary windings being connected in circuit to one of said spark plugs, the source of current having one terminal thereof grounded and having its other terminal 115 electrically connected with one end of each of said primaries, timer mechanism adapted successively to ground the other ends of said primaries, and interrupter mechanism comprising contacts adapted when closed to 120 short circuit all of the tertiary windings.

125 13. An ignition system comprising a plurality of spark plugs, a plurality of ignition coils each comprising a core and primary, secondary and tertiary windings in 125 inductive relation thereto, each of said secondary windings being connected in circuit to one of said spark plugs, the source of current having one terminal thereof grounded and having its other terminal 130

electrically connected with one end of each of said primaries, timer mechanism adapted successively to ground the other ends of said primaries, interrupter mechanism comprising contacts adapted when closed to short circuit all of the tertiary windings, a master vibrator, and switching means adapted when in one position to include the master vibrator in circuit with the current source, 10 and the several primary coils, and when in another position to eliminate the master vibrator from the primary circuit.

14. In combination, a current source, a magnetic core, a winding carried by said core and excited from said source, two other windings carried by said core, said last-

mentioned windings being in separate circuits traversed by induced currents only, first means for interrupting one of said last-mentioned circuits, a spark gap in the other 20 of said last-mentioned circuits, and second means for interrupting the circuit of the winding which is excited from said source, said first means operating prior to said second means in the cycle. 25

In witness whereof, I hereunto subscribe my name this 27th day of January, 1922.

WILLIAM W. HAWKINS.
